Primary Examiner — Rhea Shields(74) *Attorney, Agent, or Firm* — Merchant & Gould P.C.(57) **CLAIM**

The ornamental design for a cable port chassis, as shown and described.

DESCRIPTION

FIG. 1 is a top, front and right side perspective view of a cable port chassis according to our design;

FIG. 2 is a front view thereof;

FIG. 3 is a left side view thereof;

FIG. 4 is a right side view thereof;

FIG. 5 is a top view thereof; and,

FIG. 6 is a bottom view thereof, the rear not shown being devoid of ornamentation.

In the drawings, the broken lines are for the purpose of illustrating environment only and form no part of the claimed design. Shade lines having a combination of long and short lines in the Figures show contour and not surface ornamentation.
